Primary Examiner — Anhdao Doan*Assistant Examiner* — Mary Shannon Malley(57) **CLAIM**

The ornamental design for a modular storage tray, as shown and described.

DESCRIPTION

FIG. 1 is an exploded front view of a modular storage tray showing my new design, a rear view being a mirror image thereof;

FIG. 2 is an exploded left side view of the modular storage tray;

FIG. 3 is an exploded right side view of the modular storage tray;

FIG. 4 is an exploded top view of the modular storage tray;

FIG. 5 is an exploded bottom view of the modular storage tray; and,

FIG. 6 is an exploded top front side perspective view of the modular storage tray.
